UNITED STATES PATENT OFFICE.

WILLIAM J. KENNY, OF CHICAGO, ILLINOIS, ASSIGNOR OF ONE-HALF TO
WILLIAM S. CUMMING, OF CHICAGO, ILLINOIS.

MACHINE FOR END-SEAMING SHEET-METAL BODIES.

SPECIFICATION forming part of Letters Patent No. 699,843, dated May 13, 1902.

Application filed April 13, 1901. Serial No. 55,787. (No model.)

To all whom it may concern:

Be it known that I, WILLIAM J. KENNY, of Chicago, in the county of Cook and State of Illinois, have invented certain new and useful Improvements in Machines for End-Seaming Sheet-Metal Bodies; and I do hereby declare that the following is a full, clear, and exact description thereof, reference being had to the accompanying drawings, and to the letters of reference marked thereon, which form a part of this specification.

This invention relates to a novel machine employed in manufacturing cans, pails, or similar sheet-metal bodies.

15 The invention relates primarily to a novel device for uniting the body-wall with the bottom plate by means of a seam formed by folding the margin of the bottom plate over the margin of the body-wall.

20 The invention also embraces other improvements in machines of this character, as will hereinafter more fully appear.

An organized machine in which my improvements are shown as embodied embraces generally a suitable die-press, provided with a vertically-reciprocating head, on which a forming-head is mounted, a plurality of dies for holding the sheet-metal body-blank and the bottom plate in position for being operated upon by said forming-head, and a carrier for said dies, by which they are successively brought into coöperation with the forming-head.

The invention consists in the matters hereinafter set forth, and more particularly pointed out in the appended claims.

In the drawings, Figure 1 is a side elevation of a press fitted with devices embodying the principal features of my invention. Fig. 2 is a view, partially in section, taken on line 22 of Fig. 1. Fig. 3 is a vertical central section, with parts broken away, taken through the press, the forming-head, the die, and the die-carrier, showing the positions of the parts when the press-head is at the uppermost part of its stroke and showing a sheet-metal blank-body and a bottom blank placed on the die. Fig. 3^a is a view in cross-section showing a detail of a sleeve for raising the die on line 3^a 3^a of Fig. 3. Fig. 4 is a vertical central section through the forming-head, showing the side wings of the forming-head at their po-

sitions of initial engagement with the blank. Fig. 4^a is a sectional detail of one of the side wings, together with its actuating-cam, illustrating the forming-jaw in its retracted position, but before the wing has been retracted. Fig. 5 is a vertical central section through the forming-head, showing the position of the side wings in the further downward movement of the forming-head. Fig. 6 is a vertical section taken through the forming-head, showing the position of the corner-wings at the beginning of their inward movement toward the blank. Fig. 7 is a similar vertical section showing the position of the corner-jaws at the end of the downstroke of the head. Fig. 8 is a bottom plan view of the wings and heel-plates, showing the side wings projected inwardly. Fig. 9 is a similar plan view showing the corner-wings projected inwardly. Fig. 10 is a plan view of the cam-ring for actuating the wings. Fig. 11 is a view in detail in vertical section of one of the side wings. Fig. 12 is a similar detail of one of the corner-wings. Fig. 13 is a view in cross-section through the machine, taken on line 13 13 of Fig. 3. Fig. 14 is a similar sectional view taken on line 14 14 of Fig. 3. Fig. 15 is a view, partially broken away, of the heel-plate of the forming-head, showing filler-blocks therefor. Fig. 16 is a view on line 16 16 of Fig. 15. Fig. 17 is a similar view showing the filler-plates when the heel-plate is expanded. Fig. 18 is a bottom plan view, partly in section, of the wings and heel-plate, showing a modification of the forming-jaws. Fig. 19 is a section taken through one of the corner-jaws shown in Fig. 18, through the cam-ring, and a portion of the forming-head and illustrating a portion of the blank. Fig. 20 is a similar view showing the parts in position to complete the seam. Fig. 21 is a top plan view of one of the corner-jaws and a part of the cam-ring, showing in section the guide-bolts and pins for said jaws. Fig. 22 is an inside view of a segment of the cam-ring shown in Figs. 19 to 21. Fig. 23 shows the shape of the flange on which the modified form of jaws are adapted to operate.

Referring in general terms to the machine illustrated, said machine comprises a suitable die-press having the usual reciprocating head, a cam-ring supported on the press, and a form-

ing-head mounted on the press-head and passing through the cam-ring at each stroke of the press, so that its forming jaws or wings are brought into operative engagement with the cam-ring, dies suitable for carrying sheet-metal blanks, and a carrier on which said dies are mounted so as to be brought successively into position for engagement with the forming-head.

10 The machine is herein shown as adapted to be used in seaming oblong can-bodies, such as used, for instance, for making sardine-cans; but it will be understood that the machine may be adapted for operating upon sheet-15 metal bodies for other purposes and of other shapes than shown. The term "can-blank" used hereinafter is employed merely for convenience of designation.

In the drawings, A designates a die-press 20 having the usual vertical reciprocating head A' and a circular carrier-plate B, rotatively mounted on the lower portion of its frame. Said carrier is of the general form shown and described in my prior application for United 25 States Letters Patent filed March 18, 1901, Serial No. 51,587, and is not claimed herein. A cam-ring C is secured to the press below the head A'. As herein shown, said ring is secured by means of projecting lugs c' there-30 on to lugs a' on the vertical guides or column of the press, Fig. 2, so as to be in the path of the stroke of the press-head. Its vertical position relative to the press-stroke is predetermined, the usual adjusting means of the press-35 head being employed to obtain an accurate location thereof. The press-head A' carries a forming-head D, having a plurality of forming-wings, hereinafter more specifically described, adapted to be brought into contact 40 at certain portions of the stroke with cam-surfaces formed on the cam-ring C, whereby lateral movement is imparted to the wings at the time they are moved downwardly to bring said wings in position with respect to the can-45 body or blank to form the seam thereon. A plurality of dies E are mounted on the carrier B in such manner as to have limited vertical oscillatory movement in conjunction with the press-head, each being formed to carry a can-50 blank.

Referring now especially to the forming-head D, said head comprises a central head d, whose form is shown in Figs. 3, 4, 6, and 14. Said head is formed with an upwardly-55 projecting stem d', adapted to engage a vertical socket in the press-head A' in the usual manner. Said stem d' is provided with a central vertical elongated aperture which forms a pocket for a spiral spring F. The lower end 60 of said spring acts against a plunger f, which has limited vertical movement in the lower and contracted part of said socket. The lower end of said plunger projects into a central opening d² in the center of the head d and 65 comes into contact, as hereinafter more fully described, with wing-levers of the forming-head. The upper end of the spring F comes

into operative contact, as shown herein, with a horizontal bar N. Said bar N is secured transversely in the head A' of the press in a 70 suitable slot, so as to have a limited vertical movement, and is of sufficient length to project beyond the sides of the head and come into engagement at or near the upper part of the stroke of the head with lugs or stops a¹⁰, 75 which are secured to the main frame of the press. The spring F may bear against the press-head without the interposition of the bar when it is not desirable to compress the spring F at the latter part of the upstroke. 80 The tension of the spring F is sufficient to hold the bar N at the uppermost portion of its containing-slot when the bar N is not in engagement with its stops a¹⁰. Depending from said head d and pivotally supported therein on 85 trunnions are two sets of wings G and G'. One set of said wings G, hereinafter known as the "side wings," are adapted to engage the middle portions of the sides of the can-blank between the corners thereof, while the other set 90 G' are adapted to engage the sides and ends of the blank, forming the corners thereof, and are hereinafter designated as the "corner-wings." When operating on cylindric cans, the wings corresponding to the corner-wings 95 shown will have the form of arcs of a circle, and when operating on other forms of cans said wings will be varied in shape to correspond to the particular shape of the can. Referring first to the side wings G, they each comprise a 100 stem g, having trunnions g' at its upper end, which engages trunnion-blocks g², Fig. 14, so that the stem g swings in a vertical arc toward and from the center of the head d. Said trunnion-blocks g² are secured to the 105 head d by screws or other suitable means. Projecting outwardly from the upper end of the stem g is a horizontal arm g³. The outer end of the arm is provided with an aperture g¹², which permits passage therethrough of a 110 guide-pin c, secured in the cam-ring C, and the consequent engagement of the arm with a spiral spring c¹¹ in a manner hereinafter to be more fully described. At the lower end 115 of the stem g is secured a fixed horizontal plate g⁴ of the contour plainly shown in Figs. 8 and 9. Said plate is secured by means of fillister-head stud-screws g⁵, so as to form, in connection with the end surface of the stem g, a horizontal guide in which slides a plate 120 or jaw g⁶. Said jaw g⁶ is formed with a rabbit on its inner end adapted to engage the margin of an outwardly-projecting flange on the can-body and the edge of the end plate of the can-body superimposed thereon and 125 bend them down against the can-body to form a seam, as hereinafter more fully described. The outer end g⁷ of said jaw is beveled to form a cam-surface to act against the cam-surface of a portion of the cam-ring C. A 130 horizontal slot is formed in the bottom of the stem g, in which is located a spiral spring g⁸, said spring acting in compression between the end of the slot and a pin g¹¹, which is se-

cured in and projects from the upper surface of the jaw-plate g^6 into the slot. The action of the spring g^8 on the pin g^{11} is to hold the jaw g^6 in its outermost position (shown in Fig. 11) when said jaw is not in contact with the cam-ring C.

The corner-wings G' are similar to the side wings G in that they each have a stem g' and a sliding jaw g^6 secured between the ends of the stem g and a plate g^4 . They are likewise pivotally attached to the head d by trunnions g' engaging trunnion-sockets in the trunnion-block g^2 . The corner-jaws are of the contour shown in Figs. 8 and 9 in order to enable them to engage the corner portions of the can-blank. They are provided each with a horizontal arm g^{10} , which projects inwardly through a slot formed in the head d to approximately the center of the head and the opening d^2 , so that the inner end of the arm g^{10} bears with its upper surface against the lower surface of the spring-pressed plug f. The action of said plug on the arms is to keep the corner-wings in the position shown in Fig. 6 when they are not in engagement with the cam-ring.

The lower end of the head d is provided with a spring-pressed sectional presser or heel plate I, consisting of segments i, having a ball-and-socket connection with the head at the center, as plainly shown in Fig. 3, so as to be afforded an angular oscillatory movement thereon. Said connection is afforded by a screw K, secured on the lower surface of the head d, having a head consisting of a segment of a sphere and engages curved lugs projecting upwardly from the plate-segments. Spiral springs i' are inserted in apertures in the lower end of the head d and bear against the upper surfaces of the plate-sections and tend to hold the outer edges thereof down, as shown in Fig. 3. When the head is depressed, the collapsed heel-plate I is permitted to freely enter the depression in the end plate of the can, and when the head is fully depressed the segments of the heel-plate have swung upwardly on their pivots and expanded, so as to force the edges of the plate outwardly against the vertical flanges of the end plate, said outer edges of the heel-plate affording a backing against which the seaming-jaws act. In order to provide a perfect bearing-surface against the blank when the segments i are pressed back against the die-head d, filler-blocks i² are secured in the die-head d, so as to fill the spaces between the segments when thrown upwardly, the outer faces of said filler-blocks being flush with the outer faces of the segments.

Referring now to the cam-ring C, said ring comprises a ring supported, as hereinbefore stated, by suitable lugs c' c, bolted or otherwise suitably secured to lugs a on the frame of the press. The inner surface of the ring is partially formed with beveled segments forming cams c², symmetrically disposed around the interior of the ring and adapted

to engage the corner-wings G' of the former head to move the jaws g^6 radially inwardly upon the depression of the head. Obviously 70 said cam-surfaces may be straight instead of curved, as shown. Between said metal cam-surfaces c² and mounted on the upper surface of the ring are blocks c³. Said blocks are secured by screws c⁸ passing through slots in the blocks and are afforded a lateral adjustment by means of set-screws c⁴, having screw-threaded engagement with upturned lugs c⁵, formed on the ring and bearing with their inner ends against the outer ends of said 80 blocks c³. Said set-screws c⁴ are held in adjustment by lock-nuts c⁶. The inner ends of each of the blocks c³ are formed with a beveled and undercut flange c⁷, as plainly shown in Figs. 3, 4, 4^a, and 5. Said blocks are symmetrically disposed around the ring, so as to engage the beveled ends g⁷ of the slide-jaws c⁶ of the side wings of the forming-head to give to said jaws lateral movement toward the center of the press simultaneously with 90 the vertical movement of the head d, as hereinafter more fully described.

Referring now to the die, it comprises a plate E, shaped to conform to the figure of a body-blank for which the press is adapted and 95 having a raised center portion e, with beveled sides e', on which the body-blank may be set in an inverted position and centered by said beveled edges with respect to the die. If the can is to be seamed after it has been filled, 100 the die or center block will be formed to receive the can instead of entering the blank, as shown. Said plate E is mounted on a stem e², which has vertical sliding engagement with the carrier through a suitable guide aperture and whose lower end, when the die is under the head and the carrier is at rest, is adapted to engage the upper end of a plunger H, mounted in the bed of the press, as shown in Fig. 3. Said plunger H has sliding engagement at its lower end with a sleeve h, which contains a spiral spring h', the lower end of which bears against a screw-plug h², inserted in the lower end of said sleeve and the upper end of which bears against the 115 lower end of the plunger H. Said sleeve is provided with trunnions h³, which are adapted to be engaged by the forked arms k on lever K. The inner end of said lever K is raised, so as to bring the plunger H into engagement 120 with the stem e² of each die as the latter is brought by the carrier into co-operative position with respect to the forming-head. Said lever K is secured at one end to a horizontal rock-shaft K', which is rotatively mounted 125 in suitable bearings on the press-frame and carries at its end remote from the lever K a rock-arm K², which is in alinement with a slide K³, which carries the dog actuating the carrier B. On said slide is secured a limber 130 pawl K⁴, which is adapted to engage and depress the rock-arm K² during the time the slide K³ is retracted and when the die is in operative position with respect to the former-

head, and thereby raise the die toward said head. When the slide K³ moves toward the front of the machine to operate the carrier, the dog K⁴ releases the rock-arm K² and allows the inner end of the lever K and the sleeve h⁴ to drop down.

The operation of the machine as a whole is as follows: A can-blank J, having an outward flanged formed on one of its margins, is placed on the die-plate E with the flange end uppermost. A blank for a bottom plate is inserted or laid on the top of said body-blank J, said end plate having a depressed center portion to enter the upper edges of said can-body, with its margin overlapping and lying upon the outturned flange of the body-blank. By the rotation of the carrier the die-plate E is brought into register with the former-head. Immediately after this movement is effected the slide K³ is retracted and the pawl K⁴ engages the rock-arm K², whereby the inner end of the lever K is raised and the die-plate E thereby raised to the plane of the cam-ring C. While said die-plate is beginning to rise the former-head begins to descend. When the outer edges of the spring-pressed segments of the heel-plate I are brought into engagement with the end plate of the body-blank, the said plate is expanded outwardly against the flange of said plate and fits tightly therein. As the down-stroke of the press proceeds the wings G of former-head are passed down through the cam-ring and the side jaws are thrust inwardly by engagement of the beveled surfaces g⁷ on the outer ends of the jaws with the beveled surfaces of the segment c⁷ of the cam-blocks c⁸ on the ring. As the side wings are swung inwardly by this action of the cam-surfaces the inner ends of the stationary plates g⁴ grip the opposite sides of the can-blank, so as to center the blank on the die and grip the blank to hold it in place. While the former-head is descending in the manner described, the die-plate E will be moved upwardly to bring the upper end of the can-blank approximately to the plane of the upper surfaces of the blocks c⁸, so as to permit the ends of the plates g⁴ to grip the can-body below the flange thereon when moved inwardly. When the can-blank has been so gripped by the wings G, the die-plate is depressed in unison with the former-head to the position shown in Fig. 4, said depression being allowed by a sharp inclination in the rear end of the rock-arm K², with which the pawl is at this time engaged, and a slight compression of the spring h'. The spring g⁸, Fig. 11, is made of such strength as to resist compression when the plates g⁴ of the wings G are being moved against the can-body. After the can has been gripped in the manner described the further depression of the head acts to move the seaming-jaws g⁶ inwardly against the flanges of the end plate and can-body. The flange of the end plate comes first in contact with the forming-rabbit in

the jaws g⁷, the rounded inner corner of said rabbet first curling or folding the flange downwardly under the flange of the body and the continued inward movement of the jaws folding both flanges against the can-body. The springs g⁸, which are brought into compression by the inward movement of the slide-jaws, instantly throws the slide-jaws of the side wings out after they have passed the beveled edges of the blocks c⁸. At the same time the springs c¹¹ on the posts c are in engagement with the outer ends of the arms g³ of the side wings, and said springs are brought under compression by the downward movement of the former-head. When, therefore, the jaws g⁶ pass the cam-surfaces of the cam-block c⁸, said springs act to quickly throw the side wings into the position shown in Fig. 5. By these movements the central parts of the body-flange and margins of the end plate between the corners have been bent over and formed into a double seam. In the further descent of the former-head the corner-jaws are thrown forward to complete the forming of the seam. As the downward movement of the presser-head continues the lower outer corners of the fixed plates g⁴ of the wings G encounter the beveled surfaces c² of the cam-ring c, as clearly shown in Fig. 6, so that the wings are swung inwardly and the inner ends of the plates g⁴ engage the portions of the can-body below the flange and adjacent to the corners and hold the blank firmly in position, as shown in Fig. 7. As the stroke continues the forming-jaws g⁶ thereof are thrown inwardly by the action of the cam-surfaces on the ring-segments c², so that the forming-rabbets at the inner ends thereof catch the margins of the flanges in the same manner as the side forming-jaws before described to form the seams at the corners of the blank. It will be understood that during the entire downward movement of the forming-head after the heel-plate thereof comes into contact with the can-blank the die-plate moves downwardly in unison with said head. On the return movement of the follower-head the side jaws may be again thrown into contact with the seam of the blank, so as to press out any irregularities in the seam at this point, if any exist. This may be accomplished by raising the can-blank when the side wings are retracted, so that when the jaws g⁶ pass the widest parts of the cam-blocks c⁸ the seam on the body will be in position to be engaged by the forming-face of said jaws, so that said jaws will exert pressure on the seams.

It will be seen by an inspection of Figs. 8 and 9 that the acting faces of the side jaws are wider than the spaces between adjacent corner-jaws, so that said corner-jaws overlap part of the work done by the side jaws. This insures a perfect finish between the parts of the seams formed by the two jaws. From the foregoing description it will be understood that the side jaws perform their work and are

retracted before the corner-jaws are moved inwardly. By reason of the widened working faces of the side jaws it becomes important that they be retracted promptly, so as not 5 to be locked by engagement with the corner-jaws as the latter are moved inwardly. It is for this purpose that the springs g^8 are provided, which insure a prompt retraction of the jaws. It is for this purpose also that the 10 springs c^{11} are provided, which quickly throw the side wings outwardly after they have passed the cam-blocks c^3 in the descent of the follower-head.

The construction described is adapted to 15 form what is known as a "double seam." If a single seam is to be formed, the flange on the can-body is omitted and the projecting part of the flange on the end plate made narrower. Under these conditions the forming- 20 jaws merely press the end-plate flange downwardly and inwardly upon the can-body. In this event the parts of the machine are adjusted to compensate for one thickness of tin omitted—namely, the flange of the can-body.

25 In Figs. 18 to 22, inclusive, I have shown modified form of jaws and cam-ring for forming a double seam on body-blanks having flanges like those shown in Fig. 23. In said figure the end plate of the blank J is provided 30 with a flange, the intermediate part of which overlies the outturned flange of the body and the extreme margin j of which is disposed vertically and surrounds said body-flange.

In the construction shown in Figs. 18 to 22, 35 inclusive, the corner and side jaws are each made of two relatively movable parts and the cam-ring is provided with two separate cams for actuating each jaw. The corner-jaws consist of two plates g^{14} g^{15} , one above the other, 40 having slots engaged by guide-pins g^{16} , passing upwardly through the bottom plate g^{17} of the wing. g^{18} g^{19} designate pins which pass upwardly from the plate g^{14} into sockets in the wing and engage springs g^{19} therein, as 45 shown in dotted lines in Figs. 18 and 20. g^{20} designates a like pin which projects upwardly from the lower plate g^{15} through a slot in the plate g^{14} and into a centrally-located socket in the wing and engages a spring g^{21} therein.

50 Said springs g^{19} and g^{21} tend to hold the plates g^{14} and g^{15} retracted from their work. The lower plate g^{15} is provided with a central shank g^{22} , Fig. 18, which fits in a groove in the lower surface of the plate g^{14} , and the outer end of 55 said shank and the corresponding edges of the plate g^{14} are beveled. The inner part of the cam-ring C is provided with a cam projection c^{14} , adapted to engage the inclined end of the shank of the lower plate, and the ring is 60 provided below said cam projection with an inclined or cam surface c^{15} , which engages the inclined edge of the plate g^{14} . The part of the ring immediately above the inclined surface c^{15} is substantially vertical, and the ring is inclined above said vertical part, as shown at c^{16} . 65 The side jaws also consist each of an upper plate g^{24} and a lower plate g^{25} , having slots en-

gaged by a guide-plate g^{26} , similar to the guide-pins g^{16} . Said plates of the side jaws also are placed under the influence of springs like 70 the springs g^{21} , which tend to retract said plates. The movements of the side and corner jaws are substantially alike and will be described with reference to Figs. 18, 19, and 20. As the head moves downwardly the 75 lower plate g^{17} of the wings first comes in contact with the inclined surfaces c^{16} of the ring, and said wings are swung inwardly to bring the inclined ends of the shanks in contact with the cam projections c^{14} . Contact of said parts 80 in the further depression of the head causes the wings to be moved inwardly until the plates g^{17} are brought into contact with the can-body, below the flange thereof. Further depression of the wings causes the lower 85 plates of the jaws to move inwardly against the compression of the spring g^{18} to engage the vertical part j of the flange of the end plate and press the same inwardly and upwardly into the position shown in Fig. 19. 90 Immediately thereafter the shank passes the cam projection c^{14} and the lower plate g^{15} is thrown outwardly against the inclined or cam surface c^{15} . In the continued depression of the wings the plates g^{14} g^{15} are moved 95 inwardly in unison, and the action of the two plates is substantially like the similar jaws of the construction previously described, the end of the downward movement of the rings and the inner limit of movement of the jaws 100 being shown in Fig. 20. The remainder of the operation is substantially like that of the construction first described. It will be understood that the duplex side jaws are operated by inclined or cam surfaces like those 105 just described, but located above the level of the ring, as shown in the other figures of the drawings, so as to actuate the side jaws in advance of the corner-jaws, as in said previously-described construction. In practice 110 the horizontal surfaces between the projections c^{14} and the surfaces c^{15} and the extreme ends of the shanks g^{22} are slightly rounded, and the parts will be kept well oiled, so that the lower plates of the jaws will be forced inwardly in the ascent of the wings sufficiently 115 for said plates to pass said projection.

If the parts j of the flange shown in Fig. 23 be perfectly formed, the construction first described is well adapted to form the seam; 120 but it has been found in practice that in making a flange of this form there is tendency to the formation of an outwardly-curved bur on the edge of the flange. The construction last described insures that the vertical part 125 of said flange will be turned inwardly and upwardly without tendency of the flange being curled in the direction given thereto by the bur.

The several terms herein employed for designating the various parts of the machine have been employed merely for the purpose of convenience of designation and are not to be understood as limiting terms. For instance, the

jaws forming the parts of the seams at the corner of the can-body herein shown will if a can or body of other shape be operated upon be correspondingly changed and may not, in 5 fact, be strictly corner-jaws.

Many changes may be made in the details of construction without departing from the spirit of my invention, and I do not wish to be limited to the illustrated construction except as hereinafter made the subject of specific claims.

I claim as my invention—

1. A machine for the purpose stated comprising a die or support, vertically-reciprocating forming-jaws, and means for moving said jaws inwardly against a body-blank while said jaws are descending, said support being mounted to move in unison with the jaws in a part of the vertical reciprocation thereof.

2. A machine for the purpose stated, comprising a die or support, vertically-reciprocating wings pivoted to swing in vertical planes, forming-jaws carried by said wings, and means for moving said jaws inwardly 25 against a body-blank while said jaws are descending, said support being mounted to move in unison with the jaws in a part of the vertical reciprocation thereof.

3. A machine for the purpose stated, comprising a die or support, vertically-reciprocating wings pivoted to swing in vertical arcs, and forming-jaws carried by said wings and sliding horizontally therein radially toward a centrally-located body-blank.

35 4. A machine for the purpose stated, comprising a die or support, vertically-reciprocating wings pivoted to swing in vertical arcs, forming-jaws carried by said wings and movable horizontally therein, and springs applied to said jaws which tend to retract the jaws from their work.

5. A machine for the purpose stated, comprising a die or support, vertically-reciprocating wings pivoted to swing in vertical arcs, 45 forming-jaws carried by said wings and movable horizontally therein, said jaws being each made of a plurality of parts having relative horizontal movements.

6. A machine for the purpose stated comprising a die or support, vertically-reciprocating forming-jaws adapted to surround said die or support, and a cam-ring through which said jaws pass in their descent, said ring being adapted to engage at its inner margin the 55 jaws to move the same inwardly toward the die or support as the jaws descend.

7. A machine for the purpose stated comprising a die or support, vertically-reciprocating wings pivoted to swing in vertical arcs, 60 forming-jaws carried by said wings, and a cam-ring through which said jaws pass in their descent, said ring being constructed to move said jaws inwardly as the wings descend.

8. A machine for the purpose stated, comprising a die or support, vertically-reciprocating forming-jaws, a cam-ring adapted to engage the jaws to move the same inwardly

as the jaws descend, and springs applied to throw the jaws outwardly when disengaged from said cam-ring.

9. A machine for the purpose stated, comprising a die or support, a vertically-reciprocating head, wings carried by said head to swing in vertical arcs, forming-jaws sliding horizontally in said wings radially toward a 75 centrally-located body-blank, and a cam-ring constructed to move said jaws inwardly in the descent of the head.

10. A machine for the purpose stated, comprising a die or support, a vertically-reciprocating forming-head, jaws carried by said head, means for moving said jaws inwardly against a body-blank in the descent of the head, and a heel-plate adapted to enter a depression in the end plate of the blank against 85 the margins of which the jaws act, said heel-plate being non-rotative and having a continuous margin against which the jaws act.

11. A machine for the purpose stated, comprising a die or support, radially-movable 90 forming-jaws, and a collapsible heel-plate adapted to press upon the end plate of the blank-body and against the margins of which the jaws act.

12. A machine for the purpose stated, comprising a die or support, a vertically-reciprocating head, forming-jaws carried by said head, means for moving said jaws inwardly against a body-blank in the descent of the head, and a collapsible heel-plate adapted to 100 enter a depression in the end plate of the blank and against the margins of which the jaws act.

13. A machine for the purpose stated, comprising a die or support, radially-movable 105 forming-jaws, and a segmental heel-plate, the parts of which are hinged at their adjacent corners to a part which carries the jaws, and filling-pieces adapted to fill the spaces between the segments of the plate.

14. A machine for the purpose stated, comprising a die or support, a vertically-reciprocating head, jaws carried by said head, means for moving said jaws inwardly against a body-blank in the descent of the head, and a segmental heel-plate, the parts of which are hinged at their adjacent corners to the head, and against the outer margins of which, when said plate is expanded, the forming-jaws act.

15. A machine for the purpose stated, comprising a die or support, a vertically-reciprocating head, forming-jaws carried by said head, means for moving said jaws inwardly against a body-blank in the descent of the head, a segmental heel-plate, the parts of which are hinged at their adjacent corners to the head and against the outer margins of which, when the plate is expanded, the forming-jaws act, and filling-pieces projecting from the head and adapted to fill the spaces between the segments of the plates.

16. A machine for the purpose stated, comprising a die or support, radially-movable

forming-jaws arranged alternately in two sets, the jaws of one set overlapping a part of the work effected by the jaws of the other set.

5 17. A machine for the purpose stated, comprising a die or support, radially-movable forming-jaws arranged alternately in two sets, the jaws of one set overlapping a part of the work effected by the jaws of the other set, and means for advancing the jaws of one set to their work and retracting the same before the jaws of the other set are advanced to their work.

15 18. A machine for the purpose stated, comprising a die or support, vertically and horizontally movable jaws arranged alternately in two sets, the jaws of one set overlapping a part of the work effected by the jaws of the other set, and means for moving said jaws inwardly against the work as the jaws are moved downwardly.

25 19. A machine for the purpose stated, comprising a die or support, a vertically-reciprocating forming-head, forming-jaws carried thereby, said jaws being divided in two sets and the jaws of one set being arranged alternately with respect to the jaws of the other set, said jaws of one set being actuated in advance of the jaws of the other set, and means 30 for moving said jaws inwardly against the body-blank in the descent of the head.

35 20. A machine for the purpose stated, comprising a die or support, a vertically-reciprocating head, forming-jaws carried by said head, said jaws being arranged in two sets and the jaws of one set being arranged alternately with respect to the jaws of the other set, one set of said jaws being actuated in advance of the other, and the working faces of the jaws 40 of one set overlapping a part of the work effected by the jaws of the other set.

45 21. A machine for the purpose stated, comprising a die or support, two sets of jaws which have vertical and horizontal movement, the working faces of one set of jaws overlapping a part of the work effected by the jaws of the other set, means for advancing said jaws to their work and means for retracting one set of jaws from the work before the jaws of the 50 other set are advanced.

55 22. A machine for the purpose stated, comprising a die or support, vertically and horizontally movable forming-jaws, arranged in two sets, the jaws of one set being arranged alternately with respect to the jaws of the other set, means for moving said jaws inwardly as they descend, said means being constructed to move one set of jaws inwardly to their work and retract the same before the 60 jaws of the other set are advanced to their work.

65 23. A machine for the purpose stated, comprising a die or support, radially-movable jaws arranged in two sets, the jaws of one set being arranged alternately with respect to the jaws of the other set, means for moving one set of jaws horizontally to their work and

retracting the same before the jaws of the other set are advanced to their work, and means for forcing the set of jaws first actuated against the work after the second set has been retracted.

70 24. A machine for the purpose stated, comprising a die or support, vertically and horizontally movable jaws arranged in two sets, the jaws of one set being arranged alternately with respect to the jaws of the other set, a cam-ring into which said jaws are depressed and by which they are advanced inwardly against the work, said cam-ring being provided with two sets of cams, one set being arranged above the other, whereby the two sets of jaws are separately actuated, as said jaws are moved downwardly.

75 25. A machine for the purpose stated, comprising a die or support, vertically and horizontally movable jaws arranged in two sets, the jaws of one set being arranged alternately to the jaws of the other set, a cam-ring into which said jaws are depressed and by which they are advanced inwardly against the work, said cam-ring being provided with two sets of cams, one set being arranged above the other, whereby the two sets of jaws are separately actuated as said jaws are moved 80 downwardly, the jaws of one set being passed entirely below the upper set of cams, and springs applied to said last-mentioned jaws to effect a prompt retraction of said jaws after they have passed below their actuating-cams.

85 26. A machine for the purpose stated, comprising a die or support, vertically and horizontally movable jaws arranged in two sets, the jaws of one set being arranged alternately 90 with respect to the jaws of the other set, a cam-ring through which said jaws are depressed and by which they are advanced inwardly against the work, said cam-ring being provided with two sets of cams, one set above 95 the other, whereby the two sets of jaws are separately actuated as said jaws are moved downwardly, the jaws of one set being passed entirely below the upper set of cams and springs applied to said last-mentioned jaws to 100 effect a prompt retraction of said jaws after they have passed below their actuating-cams, the working faces of the jaws of the last-mentioned set being made wider than the spaces between the jaws of the other set when the 105 latter jaws are moved inwardly.

110 27. A machine for the purpose stated comprising a die or support, combined gripping and forming jaws, and means causing said jaws to first grip a body-blank to hold it in 115 place and thereafter to form a seam on said body-blank.

120 28. A machine for the purpose stated comprising a die or support, vertically-reciprocating, combined gripping and forming jaws, 125 and means causing the gripping-jaws in the first part of the descent thereof to grip the body-blank to hold it in place and thereafter in the further descent of the jaws to move the

forming-jaws inwardly to form a seam on the body-blank.

29. A machine for the purpose stated comprising a die or support, vertically-reciprocating, combined gripping and forming jaws, and means causing the gripping-jaws in the first part of the descent thereof to grip the body-blank to hold it in place and thereafter in the further descent of the jaws to move the forming-jaws inwardly to form a seam on the body-blank, said support being movable in unison with the jaws in a part of the vertical reciprocation of the latter.

30. A machine for the purpose stated comprising a die or support, vertically-reciprocating, combined gripping and forming jaws, means causing the gripping-jaws in the first part of the descent thereof to grip the body-blank to hold it in place, and thereafter in the further descent of the jaws to move the forming-jaws inwardly to form a seam on the body-

blank, and a spring applied to hold each forming-jaw to retract it with respect to its associated gripping-jaw.

31. A machine for the purpose stated comprising a die or support, a plurality of vertically - reciprocating forming - jaws, adapted when depressed to surround said die or support, and means for moving said jaws inwardly against the body-blank while said jaws are descending, said jaws being each made of a plurality of parts having relative, horizontal movement radially toward the die or support.

In testimony that I claim the foregoing as my invention I affix my signature, in presence of two witnesses, this 4th day of April, A. D. 1901.

WILLIAM J. KENNY.
